COKING RETORT OVEN

Joseph Becker, Pittsburgh, Pa., assignor, by
mesne assignments, to Koppers Company, a
corporation of Delaware

Application August 17, 1935, Serial No. 36,682

8 Claims. (CL 202—151)

My invention relates to improvements in coking retort ovens, and more particularly to horizontal coke ovens of the cross regenerative and under-jet underfired type; and preferably it is embodied in ovens of said type that are the Becker cross-over ovens of my Patents 1,374,546 and, amongst others, 1,904,191 and having the under-jet type of construction exemplified in my further Patents 1,704,239 and 2,003,574 and in certain figures of my copending application Serial No. 2,564 filed January 19, 1935; and the invention is further applicable to other cross-regenerative under-jet horizontal coke ovens.

This application is a continuation in part of my application Serial No. 30,533 filed July 9, 1935 wherein I have disclosed improvements of general utility in the coking retort oven art, by means of which more especially, the basement substructure of under-jet underfired ovens may be positively 10 and adequately ventilated by a method which utilizes the stack draft existing in the cross-regenerative and flue system of such oven batteries; and with such provision, the basement structure is cooled to give improved working conditions 20 within that space. The immediately before-mentioned invention provides for withdrawing as much as all of the combustion air required in the under-firing system of the battery structure from the basement structure which exists beneath the oven pad, and which is provided in ovens using 30 this type of construction for rendering accessible the divers devices and means used to control the introduction and distribution of heating gas along the oven walls when the battery is under-fired with rich gas. My invention provided sub-channels beneath the regenerator soles through 40 which basement atmosphere could be drawn by the stack draft into the regenerator soles and thence into the heating flues of the under-firing system. Said subsole-channels open at their inner ends into the battery basement at a point substantially median of the basement ceiling and extend from one end thereof to the other. At their outer ends, they port into the air flow boxes 50 housing the means for controlling the flow of gaseous heating media that enters the regenerative and heating flue system.

Within that invention, as aforementioned, I made provision for withdrawing combustion air requirements from the battery basement and further provided communicating openings between the battery alleys and said basement so that air removed from the latter by the stack draft would be replaced by air flowing into the 55 basement from the alley ways; thus furnishing

not only means for ventilating the basement, but for cooling the alleys as well. In order to effect this objective purposefully, provision was made to withdraw from the basement, all air required for the underfiring; and by-passing of the basement was avoided by supplying no communication between the alleys and the flow boxes therein situated.

The effectiveness of the ventilating and cooling that said invention accomplishes is better 10 realized when it is understood that the underfiring air requirements demand a complete change of air in the battery basement every four or five minutes.

Under some circumstances imposed by season 15 and climate or operating practice, the efficacy of the cooling provided by the above described ventilation expedient may be so effective as to produce an undesirable operating situation, i. e., the temperature of the rich gas flowing through the 20 basement distributing means may be reduced such that it attains a temperature below the dew-point, thereby producing condensates which will accumulate within the distribution lines and may deposit moisture in the control orifices in the branch 25 lines and disturb the uniform distribution of the heating media to the regenerators and flues.

My invention has for an object, therefore, provision of means whereby the disadvantageous contingency aforementioned may be successfully circumvented and, briefly stated, comprises providing the air-flow boxes in the alley-ways with adjustable valves, operable by the reversing mechanism, through which air may be introduced directly from the alleys into the regenerator soles 30 and which, in combination with the aforementioned subsole-channels, will allow any preferred proportion of the total combustion air requirement to be taken from the alleys or the battery 35 basement.

In this manner and by means of this novel arrangement, I provide great latitude in choosing the source of the under-firing air requirements. During periods of extremely cold weather, the 40 total combustion air used may be taken from the 45 alley-ways and the heat radiated from the battery structure into the basement, may be conserved therein to maintain the rich fuel gas in the distributing lines at a temperature above its dew-point, or during the hot seasons when atmospheric 50 temperatures are high and there exists no danger of reducing the temperatures in the distributing lines below the dew-point of the gas flowing therethrough, the total combustion air may be withdrawn from the battery basement and the 55

benefit of the ventilating and cooling advantage to the basement structure thereby obtained, realized.

In the accompanying drawings, forming a part of this specification and showing for purposes of exemplification certain preferred forms and manner in which the invention may be embodied and practiced, but without limiting the claimed invention specifically to such illustrative instance or instances:

Figure 1 shows a longitudinal cross-section in elevation through one of the ovens comprising a battery of the aforesaid cross-regenerative under-jet Becker ovens including an embodiment 15 of my invention.

Figure 2 is a section on the line II—II of Figure 1 and shows the underfiring arrangement of a plurality of ovens forming one end of an oven battery, wherein the rich-gas introduction into 20 the heating flues for underfiring purposes is effected using the under-jet principle, and the waste gases are flowed to the flues in the opposite heating-wall in the well known cross-over manner exemplified by the above-mentioned Becker 25 crossover patents, the said waste gases passing on through the waste-heat regenerators and thence to the stack disposal;

Figure 3 shows an elevational view, parts in 30 section, of a type of flow-box construction showing the disposition of the valves and their actuating means which may be used to control the air and waste-heat flow in this exemplification of my invention;

Figure 4 shows a plan view of the same flow-box 35 construction.

Figure 5 is a horizontal sectional view through the battery on the line V—V of Figure 1, to show in plan the arrangement of the subsole-channels that my invention provides beneath the cross- 40 regenerator sole-channels and just above the pad that directly supports the regenerators of the battery, to provide for the intake of air from the battery sub-structure and for the distribution and delivery of such air to the regenerator sole-channels;

Figure 6 is a horizontal sectional view taken through the battery along lines VI—VI of Figure 1 to show the arrangement of the supporting piers and work-passages in the sub-structure of 50 the battery and also the disposition of the rich-gas main and of the lateral waste-gas tunnel structures on the coke-side and pusher-side respectively of the sub-structure of the battery;

Figure 7 is a horizontal sectional view taken on 55 lines VII—VII of Figure 1.

Like reference numerals indicate like parts in all of the above figures of the drawings.

The coking retort oven or oven battery comprises a series of horizontal coking-chambers 60 10 and intermediate heating-walls 12 therefor and side-by-side therewith, and series of side-by-side regenerators 13, 14 below and paralleling the series of coking-chambers and heating-walls. The heating-walls comprise vertical heating-flues 65 15 disposed in sets in each heating-wall, the sets or pairs of mutually adjacent heating-walls being mutually connected by crossover-conduits 16 through which the hot combustion products or waste-heat gases from the up-flow or burning set 70 70 of heating-flues in one heating-wall flow over to the down-flow set of heating-flues in the other heating-wall of the pair, the up-flow being reversed and the up-flow set becoming the down-flow set and vice versa upon the reversal of the regenerative system. The aforesaid cross-regen-

erators, below and paralleling the series of coking-chambers and heating walls, are directly supported on a pad or mat 11 and are disposed in groups of four, each group having two middle regenerators 13, 13 that may be employed for pre-heating poor or weak gas and are flanked by air regenerators 14, 14, or all four regenerators in the group 13, 13, 14, 14 may be employed for preheating air when the oven is underfired with rich gas from its under-jet connections. At any given time, alternate groups of regenerators operate for up-flow of air, or of preheated gas and air, and the intermediate groups for down-flow of waste gases, these relations being reversed in each period of reversal of the regenerative system. 10 15 The regenerators 13, 13 at their tops connect through ducts 17, 17 with heating-flues in heating-walls that are on respectively opposite sides of the coking-chambers directly above such pair of regenerators 13, 13; and the two regenerators 20 14, 14 which flank said regenerators 13, 13 in each group, each communicate respectively, through ducts 18, with the heating-flues in one of the said two heating-walls that are both in connection with said regenerators 13, 13. Such two 25 heating-walls operate simultaneously in the same direction in respect of each other and respectively belong to two adjacent pairs of the pairs of heating-walls that are connected by cross-over conduits 16 in the manner before described. The 30 pillar-walls 23, supporting the battery sub-structure, that are between each pair of regenerators 13, 14 that simultaneously operate in the same direction, are provided with gas ducts that lead from the heating-flue at the top of such pillar- 35 wall down through the pillar-wall and the underlying pad to the under-jet connections beneath the pad that communicate with the rich-gas supply conduits and main in the passages of the sub-structure of the battery. 40

When underfiring with rich gas, that is with gas which is produced as a result of the distillation or coking process, the same is introduced into the battery structure from the gas main 20 in the battery basement. This main parallels the 45 length-wise axis of the battery its entire length. At intervals along this gas main and rising perpendicularly therefrom, are found the branch lines 21 which are communicably connected with the distributing lines 22 situated beneath each 50 series of vertically disposed heating flues in an oven wall and extending substantially parallel thereto the entire length of each flue series. Each heating flue 15 (Figure 2) is supplied at its lower end with rich gas by means of the vertically 55 rising ducts 19 which extend from the branch lines 22 through the oven-pad and the regenerator pillar-walls 23, to the gas nozzles situated at the base of each flue. The volume of gas flowing each distributor line 22, is regulated by means 60 of the valve 47; and graduated orifice-plates, which may be changed from time to time, are provided in the accessible lower ends of the gas-ducts that extend up from the sub-structure passage-ways to the bases of the individual flame- 65 flues.

Each regenerator has the usual sole-flue 24, and beneath each regenerator sole-flue 24, and extending approximately parallel therewith throughout its length, there is a ventilating duct 70 or subsole-channel 25 which is or structurally lies atop the oven-pad 11. Those four subsole-channels 25 lying beneath the sole-flues 24 of the four regenerator sections serving the heating-flues communicably connected with one series of 75

cross-over flues, are inter-connected by means of lateral ducts 26 near their outer ends. At the inner end of each subsole-channel and adjacent to the regenerator division wall 27 extending the lengthwise axis of the battery, there is a port 28 which connects said channel with the basement atmosphere substantially as shown. The quantity of air flowing into the subsole-channels 25 is controlled by preferred adjustments on the valve 29, and as it progresses along said subsole-channels, the air absorbs heat from the oven-pad and the brick-work at the base of the sole-flues. Having traversed the length of subsole-channel, this air then passes through valve 30, as shown by the arrows (Figure 1) and enters the regenerator sole-flue 24, where it is distributed to the checker-brick above through the communicating openings 31.

Mechanical means are not necessary to effect the passage of air through the subsole-channel, the stack draft and chimney effect in the regenerators and heating-flues being sufficient for that purpose.

For effecting the reverse interval of gaseous flow in the regenerative heating cycle, when the former flame-flues become the waste-heat flues and those regenerators which served for the inflow of air then carry the products of combustion to the stack, I have provided a novel mechanical device to accomplish the periodic flow reversal, as is shown in Figures 3 and 4. I have also provided means for maintaining a flow of air in those subsole-channels 25 which at one period of the heating cycle lie beneath the sole-flues serving to flow combustion products from the regenerators into a waste heat tunnel 32, and which therefore do not discharge air into the regenerator sole-flues 24 above.

Referring to Figures 3 and 4, the flow-box 33 is communicably connected by means of the pipe 34 with one of the waste-heat tunnels 32, and at one end bifurcates and by suitable sleeve connections 35 and packing is held in gas-tight connection with the regenerator sole-flues 24. Within each sleeve 35 is found a valve 30 which is operable by movement of the links 36 to open or close as preferred. Each valve 30 is provided with a valve-seat 31. Communication between the waste-heat tunnel 32 and the regenerator sole-flues 24 is established or broken by respectively opening or closing the valve 38 situated in the flow-box 33 at its junction with pipe 34. The valve 38 may be opened or closed by raising or lowering the counter-weight 39. The two valves 30 and valve 38 contained within one flow-box and serving two regenerator halves, are joined by the suitable lever links 36 and 40 so as to be actuated in unison by movement of the reversing cable 41 and in such manner as to close the valves 30 while opening 38 and vice versa. The damper valves 42 are manually operable to obtain preferred draft suction in either sole-flue.

As beforementioned, when air is no longer to be introduced through the valves 30 from the subsole-channels 25 into the sole-flues 24 and a new period of the heating cycle is to be initiated, the reversing cable is appropriately moved and the connecting chain moving over the pulley 43 raises the counterweight 39, simultaneously effecting the closing of both valves 30 and opening of the valve 38, thereby establishing communication between the waste-heat tunnel 32 and the sole-flues 24.

By the same movement of the reversing cable, similar valves in the adjacent flow-box associ-

ated with the other pair of sole-flues communicating, through the other regenerators and heating-wall, with the same series of cross-over flues near the top of the battery, are moved into the reverse position, i. e., their valves 30 are opened 5 and valve 38 is closed, thus permitting air to flow from the subsole-channels 25 into the regenerator sole-flues on the opposite side of the flow reversal plane.

From the aforesigned description of my invention it is apparent that the flow of air through the subsole-channels 25 is effected by the natural draft in the heating flues and the combustion-products discharge-stack. With the closing of the valves 30 at the end of a period of the regenerative heating cycle and the consequent severing of communication between the sole-flues and their subsole-channels beneath, this agency to effect the movement of air in the subsole-channels is cut off. During one-half of the heating cycle, therefore, relatively little beneficial effect would be obtained from the presence on one-half of these ventilating means in the battery structure. To obviate this situation, and provide a flow of air in all subsole-channels during both periods of the heating cycle, I interconnect near their outer ends by means of the ducts 26, the subsole-channels beneath those sole-flues which alternately supply air to or carry the products of combustion from those heating 30 flues which are communicably connected as aforesaid by the same series of cross-over conduits 16. In this manner, all said subsole-channels are provided with a free flow path to the stack at all times; alternately, through the sole-flues directly above or by way of the ducts 26 and the adjacently associated subsole-channels. 35

All air introduced into the battery for combustion purposes may be drawn from the battery basement passages 45, as shown by the arrows 40 in Figure 1. A constantly changing flow of air through the alley-ways 44, the battery sub-structure passages 45 and the subsole-channels 25 is thereby maintained which serves to cool 45 these parts of the battery structure and give improved operating conditions therein. The obvious benefits derived from so introducing all the combustion air into the battery will obtain in those geographical positions or during those seasons of the year that the atmospheric temperatures permit of so doing without reducing the temperatures of the fuel gas flowing through the distributing lines, as for example 19, 20 and 22, below its dew point. When, however, the atmospheric temperatures reach a level that such 55 practice reduces the temperature of the gas in the distributing means to a point where condensates begin to form therein and it therefore becomes necessary to reduce the amount of cooling of the battery basement that is effected by 60 flowing the total combustion air requirements therethrough, I provide means whereby only that quantity of the combustion air may be removed from the battery basement which will give the 65 preferred operating temperatures therein and the remainder may be obtained from the alley-ways. In other words, I furnish a combination of air-supplying means which permits me to use either the battery alleys or the basement individually as the total source of underfiring air supply or to so proportion air derived from the two sources that the maximum cooling of the basement will be effected that will give rise to no formation of condensates in the fuel gas distributing lines. 70 75

By means, therefore, of the valve 50 in the flow-box 33, air may be introduced directly from the alley-ways into the sole-channels 24 in regulable amounts where it will be admixed, before flowing into the regenerator checker-brick above, with any air arriving therein by way of subsole-channels 25 and valve 30. By means of the chain 51 which communicates with the reversing cable in the well-known manner, valve 50 may be opened and closed simultaneously with the opening and closing of valve 30 during the periods of flow reversal in the flue system.

It, therefore, becomes apparent that by means of the regulable valves 29 and 50 and proper adjustments thereof, combustion air from the two possible zones of origin may be admixed in any preferred proportion and that the flue and stack-drafts still serve as the supplying means for introducing the mixture into the heating flue system.

In my invention, that combustion air for the battery which is derived from the basement structure is taken from points substantially median of and distributed along the basement roof from one end to the other of the battery, and the air is drawn from directions that extend crosswise of the battery, from the open topped alley-ways on the pusher side and coke side respectively toward the median line of intakes to the subsole-channels, so that not only is the warmest air in the substructure basement passages removed first but also the withdrawal is uniformly distributed over the whole area and is positive and controlled independently of outside atmospheric conditions.

A better appreciation will be obtained of the extent of the temperature control that is effected by thus maintaining a positive flow into and complete replacement of the air in the alley-ways and battery basement, when it is realized that a battery coking 1000 tons of coal per day will consume approximately 800 tons of air for the battery underfiring, and the flowing of only a portion of this amount through the battery basement will be a significant contribution toward maintaining a more comfortable operating environment therein.

My invention, therefore, provides positive and effective means for maintaining suitable, advantageous and improved operating conditions in the basement structure of a battery of the aforementioned type. It readily adapts itself to adjustments which will meet requirements imposed by changing seasonal conditions and so permits maintaining, within the battery basement, substantially uniform and preferred temperatures at all times. The temperature within the fuel gas distribution lines can be uniformly held above the dew point of the distributed gas and any heat radiated from the above lying regenerators, which may be in excess of the amount required to meet that condition, may be dissipated, if preferred. In winter all or a substantial proportion of the combustion air may be introduced into the regenerators from the alley-ways and the heat radiated to the basement retained there, whereas in summer, the majority if not the total combustion air requirement may be withdrawn from the basement to assist in dispersing excessive heat that may tend to collect therein.

Referring to Figure 5, it will be noted that a substantial proportion of the zone between the oven-pad and the substructure comprises air spaces, which are good insulation media, serving as a barrier against heat transfer from the re-

generators to the pad and basement structure beneath, the efficiency of which is augmented by the continuously changing air flowing therethrough which is being replaced by air at a lower temperature. For circumstances where high temperatures would be otherwise inclined to prevail, this feature alone is of special importance.

To facilitate removal of dust or the like which may be deposited by the air passing through the ventilating channels and also make accessible for adjustments the valve 30, the removable plate 46 is provided. An air blast or any preferred means may be used to effect the dust removal.

The invention as hereinabove set forth is embodied in particular form and manner but may be variously embodied within the scope of the claims hereinafter made.

I claim:

1. In a battery of coking retort ovens, in combination a series of alternate coking retort chambers and flued heating walls therefor arranged side-by-side in a row, cross regenerators beneath said chambers and paralleling the same and having sole-channels communicating with the regenerators, a structural pad supporting said regenerators and their sole channels and itself supported above a sub-structure providing accessible passage-ways throughout the basement of the battery, a system of under-jet underfiring for said heating walls and accessible in said passage-ways, a series of subsole-channels intermediate the pad and the sole-channels of the regenerator chambers and paralleling the latter, said subsole-channels having air inlets arranged for intake of air along the middle line of the basement roof at the longitudinal median line of said row and said subsole-channels communicating through ports at their outer ends with the sole-channels, a series of air-flow boxes for introducing underfiring air into the regenerators, said air-flow boxes having communicable connections directly with the atmosphere in the battery alley-ways and with said sole-channels at their outer part, valve-means for the basement air inlets to the sub-sole channels and for the communicable connections of the air flow boxes to the atmosphere whereby air may be taken into the sole channels either from the basement or from the alley-ways, and said battery having openings along the pusher-side and coke-side of the basement for in-draft of air from the outside atmosphere and maintaining through the basement cross drafts from said side openings to said sub-sole-channel intakes along the middle line of the basement roof at the longitudinal median line of said row.

2. A coke oven battery as in claim 1 and having waste-heat valved-means for controlling outflow of waste-gas from the sole channels to waste-gas offtake-means, and valve means for disconnecting communication between the regenerators and the basement and outside atmosphere during operation of said waste-heat valved-means to open position for the waste-heat outflow periods of the reversal of such regenerators.

3. In a battery of coking retort ovens, in combination a series of alternate coking retort chambers and flued walls therefor arranged side-by-side in a row, cross regenerators beneath said chambers and paralleling the same and having sole-channels communicating with the regenerators, a structural pad supporting said regenerators and their sole-channels and itself supported above a sub-structure providing accessible passage-ways throughout the basement of the bat-

5 tery, a system of under-jet underfiring for said heating walls and accessible in said passage-ways, a series of subsole-channels below the regenerator chambers and paralleling the latter, said subsole-channels having air inlets arranged for intake of air along the middle line of the basement roof at the longitudinal median line of said row and said subsole-channels communicating through ports at their outer ends with the sole flues of the 10 regenerators, a series of air-flow boxes for introducing underfiring air into the regenerators, said air-flow boxes having communicable connections directly with the outside atmosphere at the coke- and pusher-sides of the battery and with said 15 sole-channels at their outer part, valve-means for the basement air inlets to the sub-sole channels and for the communicable connections of the air flow boxes to the atmosphere whereby air may be taken into the sole channels either from 20 the basement or from the atmosphere at the coke- and pusher-sides of the battery, and said battery having openings along the pusher-side and coke-side of the basement for in-draft of air from the outside atmosphere and maintaining 25 through the basement cross drafts from said side openings to said subsole-channel intakes along the middle line of the basement roof at the longitudinal median line of said row.

4. In a battery of coking retort ovens, in combination a series of alternate coking retort chambers and flued heating walls therefor arranged side-by-side in a row, cross regenerators beneath said chambers and paralleling the same and having sole-channels communicating with the regenerators, a structural pad supporting said regenerators and their sole-channels and itself supported above a sub-structure providing accessible passage-ways throughout the basement of the battery, a system of under-jet underfiring 40 for said heating walls and accessible in said passage-ways, a series of subsole-channels adjacent said pad and below and parallel with the sole-channels of the regenerators, said subsole-channels porting at their outer ends into the regenerator sole-channels and having air inlets arranged for intake of basement air at the longitudinal median line of said row, communicating means for communication between the regenerators and the outside air separately from communication of the regenerators with the basement air through the basement air inlets therefor, and regulable valve-means for both the air inlets in the basement and for said communicating means adapted to apportion the underfiring air 55 requirements of the battery between the basement derived and outside derived air.

5. A coke oven battery as in claim 4 and having waste-heat tunnels directly communicating with the regenerator sole-channels, and valve connections for separately controlling the flow of waste gas to the tunnels from the regenerators and of air to the regenerators from the subsole-channels and the outside air.

6. In a coking oven retort battery comprising a row of cross-regenerative coking chambers supported on a structural pad elevated above accessible basement passage-ways, the ovens extending substantially parallel with and alternately disposed between series of vertically disposed heating flues, with regenerators beneath, the underfiring flow reversal planes being substantially parallel with the lengthwise axis of the coking

chambers, beneath the regenerator sole-channels and the pad a series of flow channels having discharging ports porting into the regenerator sole-channels and inlet ports communicating with the basement air near the longitudinal median line of said row to carry the air underfiring requirement of the battery, those channels porting into the regenerator sole-channels which alternately carry combustion air to or the products of combustion from communicating heating flues 10 being interconnected, means for establishing communication between the regenerators on opposite sides of the flow reversal plane with the waste heat tunnel and with the outside air and the underlying flow channel series in alternation with 15 each other.

7. A battery of horizontal coking retort ovens comprising, in combination, a series of alternate coking chambers and intermediate heating walls therefor arranged side-by-side with a series of cross-regenerators therefor beneath and paralleling the same, a structural pad supporting said regenerators and itself supported above a sub-structure providing accessible passageways throughout the basement of the battery, a system 20 of under-jet firing for said heating walls comprising fuel gas connections leading from the basement directly to the heating flues and accessible from the basement and valved air-conduit connections leading from the basement to the 25 regenerators for conveying the air for combustion from the basement to the regenerators for pre-heating for combustion, and a waste gas flue alongside the basement on at least one longitudinal side of the battery and having valved connections for off-flow of waste gas from the regenerators, openings being provided all along both the pusher-side and coke-side of the basement for in-draft of the combustion air requirements of the battery into the basement from the 30 outside atmosphere, the air inlets for substantially all of the air-conduit connections which lead from the basement to the regenerators being arranged and concentrated at substantially the region of the lengthwise middle of the top part 35 of the basement so as to maintain throughout the basement, from the side openings at the cooler longitudinal coke- and pusher-sides of the battery all the way into the warmer lengthwise middle region of the basement, ventilating cross-drafts of the total volume of combustion air for 40 the basement regenerator air inlets, with all air supplied to the regenerators from the basement by the regenerator air inlets therein confined to air substantially solely from the warmer lengthwise middle region of the basement, air inflow boxes having valved communicable connections 45 directly with the atmosphere and with the regenerators at the coke- and pusher-sides of the battery whereby air may be taken into the regenerators either from the basement or directly from the atmosphere at the coke- and pusher-sides of the battery.

8. A coke oven battery as claimed in claim 7, and in which the valved connections for the air 50 inflow boxes and for the basement air inlets are independently adjustable valves for apportioning the underfiring air requirements of the battery between the basement-derived air and the outside-derived air.

JOSEPH BECKER.
